G. A. BENDER

COLLAPSIBLE CASE

Filed Oct. 28, 1925

INVENTOR:
George A. Bender
Y Jas. R. Snyder
ATTORNEY.

UNITED STATES PATENT OFFICE.

GEORGE A. BENDER, OF PITTSBURGH, PENNSYLVANIA.

COLLAPSIBLE CASE.

Application filed October 28, 1925. Serial No. 65,383.

My invention relates to shipping cases, more particularly to collapsible shipping cases, and has for its general object to provide a simple and efficient case which may be expeditiously and conveniently set up for shipping or folded in a most compact form for reshipping. And to these ends the invention consists in providing the case with a plurality of hingedly connected sections so connected and arranged that the case can be securely locked in either the set-up or knocked-down position.

With the foregoing and other objects in view the invention consists of the novel construction, combination and arrangement of parts as hereinafter more specifically described and illustrated in the accompanying drawing, wherein is shown an embodiment of the invention, but it is to be understood that changes, variations and modifications may be resorted to which come within the scope of the claims hereunto appended.

In the drawing forming a portion of this specification and wherein like numerals of reference designate corresponding parts throughout the several views:—

Figure 1 is a perspective view of the shipping case in its set-up position.

Figure 2 is a sectional view on line II—II, Figure 1.

Figure 3 is a side view of the case in the knocked-down or folded position.

Figure 4 is a fragmentary perspective view of the collapsible portion of the side wall of the case.

Figure 5 is a fragmentary perspective view of side wall securing members.

Referring in detail to the drawing 1 denotes the bottom of the case, provided with fixed front and rear side wall portions 2 and 3 respectively, and with fixed end wall portions 4 and 5. The bottom 1 and the fixed side wall portions 2 and 3 and the fixed end wall portions 4 and 5, are substantially reinforced by corner plates 6. The side wall portions 2 and 3 are of less height than the end wall portions 4 and 5 and are positioned between the latter.

The fixed end wall portion 4 is connected with a hinged end wall portion 7 by a pair of hinges 8, and the fixed end wall portion 5 is connected with a hinged end wall portion

9 by a pair of hinges 10. The hinges 8 and 10 are disposed on the inner side of respective end wall portions and permit of the hinged end wall portions 7 and 9 to be folded inwardly toward each other in a manner hereinafter described.

A pair of angle bars 11 is carried by each of the hinged end wall portions 7 and 9, by having the bar portions 12 riveted to the outer marginal side edges thereof. The bar portions 13 are formed with inwardly disposed ears 14 which are preferably stamped directly from the former. The ears 14 are vertically aligned, relatively to each other and are attached at their lower ends and free at their upper ends. The lower ends 13' of the bar portions 13, extend below the tops of respective fixed side wall portions 2 and 3, for the purpose of providing a more substantial structure.

The fixed front side wall portion 2 is connected to a hinged side wall portion 15, by means of a pair of hinges 16, and the fixed rear side wall portion 3 is connected to a hinged side wall portion 17 by means of a pair of hinges 18.

The hinges 16 and 18 are positioned on the inner face of the side walls and the lower strap 19 of each carries a fixed pin 20, which latter is shiftably connected in the vertically disposed elongated slot 21 formed in the plate 22. The plate 22 is fixed on the inner face of respective fixed side wall portions 2 and 3. The upper strap 23, of each of the hinges 16 and 18, is formed with an elongated slot 24, through which extends the headed pin 25. The latter is fixed to a plate 26 secured to respective hinged side wall portions 15 and 17.

The hinged front side wall portion 15 consists of a pair of sections 27 and 28, and the hinged rear side wall portion 17 consists of a pair of sections 29 and 30. The sections 27 and 28 are connected by a pair of hinges 31, and the sections 27 and 30 are connected by a pair of hinges 32. The hinges 31 and 32 are disposed on the outer face of respective side wall sections.

The cover 33 consists preferably of a pair of sections 34 and 35, which are connected together by a pair of hinges 36 disposed on the inner face thereof. The cover section

35 is connected to the top rear side wall section 29 by a pair of inwardly disposed hinges 37. The strap 38, of each of the hinges 37, is formed with an elongated slot 39, through which extends a headed pin 40. The latter is fixed to a plate 41 secured to the under face of the cover section 35.

A connecting plate 42 is fixed to the outer side of and adjacent to each end of side wall sections 27 and 29, and a connecting plate 43 is fixed to the outer side of and adjacent to each end of the side wall sections 28 and 30. The plates 42 and 43 at the ends of associated side wall sections are vertically aligned relatively to each other, and are provided with vertically aligned bayonet slots 44, positioned over cavities formed in respective side wall sections. The ears 14, of the bar portions 13 are adapted to engage in the slots 44 for securing the hinged side wall portions 15 and 17 and the hinged end wall portions 7 and 9 in the erected position.

A pair of rounded catches 45 are fixed to the outer side of each of the fixed side wall portions 2 and 3. The catches 45 are disposed adjacent to the upper end of the fixed side wall portions 2 and 3 and are adapted to be respectively engaged in the apertures 46, formed in the upper ends of the bar portions 13, for locking the case in the collapsed or folded position.

The cover 33 is disposed between the hinged end wall portions 7 and 9 and is secured in the closed position by a plurality of screws 47, threadably mounted in the marginal top edge of the wall portions 7 and 9 and engaging threaded apertures 48 formed in respective end edges of the cover 33.

The case is folded together in the following manner: The cover 33 is first opened by releasing the screws 47. By pulling the front hinged side portion 15 upwardly a distance permitted by the slots 24 in the hinges 16, the slots 44 will disengage the ears 14. The front hinged side wall portion 15 may now be swung inwardly on the hinges 16, and forced adjacent to the bottom 1 due to the shiftable connection of the hinge strap 19 with the elongated slot 21. The side wall section 27 is then turned back on the hinges 31 to overlap the side wall section 28. When the front hinged side wall portion 15 is folded in this manner the top thereof will be below the even plane of the top edge of the fixed front side wall portion 2.

The rear hinged side wall portion 17 is folded together in a manner identical to that described herein relatively to the front hinged side wall portion 15.

The cover 33 is forced rearwardly a distance permitted by the slots 39 in the hinge straps 38 to allow the inner marginal rear side edge of the cover 33 to seat on the top edge of the rear fixed side wall 3, while the

inner marginal front edge of the cover 33 seats on the top edge of the front fixed side wall 2. The hinged end wall portions 7 and 9 are now swung inwardly toward each other on top of the cover 33, and the bar apertures 46 forced into the catches 45, thereby locking the case in the folded position.

In setting up the case to the erected position the operations, described above relatively to folding the case, are simply reversed and are obvious to one skilled in the art to which the invention appertains.

What I claim is:

1. In combination, a collapsible case comprising a bottom, a pair of side walls, a pair of end walls, each of said pair of end walls consisting of a lower portion fixed to said bottom and of an upper portion hingedly connected to the fixed lower portion thereof, each of said pair of side walls consisting of a fixed lower portion and shiftable, foldable upper portion, a shiftable hinged connection slidably connected to the lower side wall portion and having the upper side wall portion slidably connected therewith and providing for the upward shifting of said upper portion to release it from set position and the downward shifting thereof on the lower side wall portion to permit of the upper side wall portion folding inwardly with respect to the lower portion, the upper portion of each of said side walls consisting of two sections hinged together, a cover having a shiftable hinged connection with one of said side walls, means for detachably securing the hinged portions of said end and side walls in upright position, and means for locking said cover in the closed position.

2. In combination, a collapsible case comprising a bottom provided with fixed side wall portions and with fixed end wall portions, said fixed end wall portions being of a greater height than said fixed side wall portions, an upper end wall portion hingedly connected to each of said fixed end wall portions, a pair of upper side wall portions, a pair of hinges connecting each of said pair of upper side wall portions with respective fixed side wall portions, said pair of hinges having a shiftable connection with said fixed side wall portions and said upper side wall portions having a shiftable connection relatively to said pair of hinges, and these latter providing for the upward shifting of said upper side wall portions to release them from set position and for the downward shifting thereof on the lower side wall portions to permit of the upper side wall portions being nested, each of said upper side wall portions consisting of a pair of sections hingedly connected together, means carried by said upper end wall portions and engaging said upper side wall portions for detachably securing the latter and said upper end wall portions in the

erected position, means carried by said upper end wall portions and engaging respective fixed side wall portions for locking the case in the folded position, a cover, a pair of 5 hinges connecting said cover with one of said pair of upper side wall portions, said cover having a shiftable connection relatively to the associated pair of hinges, and means carried by said upper end wall portions and engaging said cover for locking the latter 10 in the closed position, substantially as described and for the purpose set forth.

In testimony whereof I affix my signature.

GEORGE A. BENDER.
